ELECTRIC HAND VIBRATOR FOR THERAPEUTIC USE OR SIMILAR ARTICLE

Samuel L. McNair, Whitman, Mass.

Application August 14, 1953, Serial No. 26,452

Term of patent 14 years

(Cl. D83—1)

To all whom it may concern:

Be it known that I, Samuel L. McNair, a citizen of the United States, residing at Whitman in the county of Plymouth, in the Commonwealth of Massachusetts, have invented a new, original, and ornamental Design for an Electric Hand Vibrator for Therapeutic Use or Similar Article, of which the following is a specification, reference being had to the accompanying drawing, forming a part thereof, in which:

Figure 1 is a top plan view, Figure 2 is a bottom plan view, Figure 3 is a rear elevational view, Figure 4 is a side elevational view, Figure 5 is a front elevational view, and Figure 6 is a perspec-

tive view on a smaller scale, of an electric hand vibrator for therapeutic use embodying my new design.

I claim:

The ornamental design for an electric hand vibrator for therapeutic use or similar article, substantially as shown.

SAMUEL L. MCNAIR.
